UNITED STATES PATENT OFFICE.

OTTO LIETZENMAYER, OF MUNICH, GERMANY.

FUEL-PUMP FOR INTERNAL-COMBUSTION ENGINES.

1,065,004.

Specification of Letters Patent. Patented Apr. 28, 1914.

Original application filed March 4, 1907, Serial No. 360,455. Divided and this application filed April 1, 1910. Serial No. 552,814.

To all whom it may concern:

Be it known that I, OTTO LIETZENMAYER, citizen of the Empire of Germany, residing at Munich, Kingdom of Bavaria, Germany, have invented certain new and useful Improvements in Fuel-Pumps for Internal-Combustion Engines; and I do hereby declare the following to be a full, clear, and exact description of the invention, such as 10 will enable others skilled in the art to which it appertains to make and use the same.

This invention is a division of an application filed by me March 4, 1907, Serial No. 360,455 and relates to fuel pumps for internal combustion motors and the same has particular reference to means for automatically adjusting or regulating the amount of fuel fed to the motor, according to the load or, in other words, according to the speed of the 20 motor.

My invention comprises for this purpose a mechanism acting in conjunction with a governor whereby the stroke of the pump plunger for drawing in the fuel from the 25 fuel supply, or for forcing the fuel forward to the engine, or both, is varied according to the speed with which the governor revolves.

My invention also comprises such further features, combinations of parts, and details 30 of construction as will be hereinafter described and then particularly pointed out in the claims.

The drawing accompanying this specification represents a vertical central section 35 of a fuel pump embodying my invention.

Referring to the drawing, it will be noted that the fuel pump A is provided with a fuel inlet i and fuel outlet o, of any usual or suitable construction, the said inlet and outlet being governed by the suction valve s, and the pressure valve p, as will be understood. The chamber a of the pump communicates with the outlet o, through the pressure valve p, by the fuel duct a'. The 40 drawing-in and feeding forward of the liquid fuel is performed by the plungers P and P' in the manner now to be set forth.

The plunger P, which passes through a suitable stuffing box, as shown, into the 45 chamber a, is connected to a crank c by the pitman c', the said crank being operated from the internal combustion motor in any usual or desired way. To the connecting point c'', between the pitman c' and plunger P, is connected a link-rod c' whose fulcrum

f is connected to the vertical sliding part g of the centrifugal governor G, as shown.

The counter-plunger P' is actuated in partial opposition to the plunger P by the following arrangement: The lower portion 60 of the plunger passes through a bracket a' secured to the body of the pump A and ends in a head p', between which head and the bracket a' is arranged a helical spring p' 65 encircling the part of the plunger which projects below the bracket a'. This lower portion of the plunger, as shown, is reduced in cross section, and at its upper portion it passes through an arm h which, by nuts h', h'', may be adjusted on a slide-rod H, said 70 slide-rod being, for this purpose, threaded at its lower end, as shown. The said slide-rod passes loosely through a projection on the body of the pump A, as shown, and is connected by a link h' to the link c'. The 75 reduced portion of the plunger P' passes loosely through the arm h, said arm in its upward movement bearing against the shoulder p' formed at the beginning of the said reduced portion of the plunger P'. The reduced portion of the plunger P' carries below the arm h a stop p', which, as shown, 80 consists of a nut which may be adjusted vertically on screw threads cut in the lower portion of the reduced portion of the plunger. 85

The pump so constructed operates as follows: The crank when revolving causes the plunger P to reciprocate with respect to the pump chamber. In its upward movement it causes the fuel to be drawn in to the pump 90 chamber through the inlet i and suction valve s. On its downward movement it acts to force the fuel through the ducts a', the valve p, and the outlet o to the point of combustion, all in the usual manner. During the downward movement of the plunger P the slide rod H is carried downward by the link c' which rocks on the fulcrum f and thereby the arm h moves downwardly, allowing the counter-plunger P' to be urged 95 downward by the spring p' acting on the head p', until the stop p' strikes the bracket a'. The arm h continuing its downward movement, slides along the lower reduced portion of the plunger P' until the downward stroke of the slide-rod H is completed. During this motion the plunger P' remains 100 stationary and the plunger P moving toward it, in reducing the space in the pump chamber, forces the liquid fuel out of the 105 110

same through the duct a' and outlet o . When the plunger P has completed its down-stroke the continuing movement of the crank c raises the said plunger P , but during the first portion of this upward stroke of said plunger P the counter-plunger P' remains stationary, the arm h sliding upwardly on its reduced portion until it strikes the shoulder p^4 when the arm h , continuing its upward movement, moves the plunger P' upward together with the plunger P . During the first part of the upward motion of the plunger P the same therefore acts as a suction plunger, causing the liquid fuel to be drawn in to the pump chamber a through the inlet i by way of the suction valve s . If, now, there is a change of load or a change in speed of the machine, the governor G will raise or lower the fulcrum f of the link c^2 , this raising or lowering of the fulcrum f shortens or lengthens the stroke of the plunger P' for by raising the fulcrum f this raises the slide rod H which will provide that the arm h shall act against the shoulder p^4 for a greater part of a revolution of the crank C and thereby increase the stroke of P' . The converse is true when the fulcrum f is lowered by means of the governor and in this case the slide rod H will be lowered which signifies that the arm h will act upon the shoulder p^4 for a small part of a revolution of the crank C which therefore shortens the stroke of the plunger P' .

What I claim and desire to secure by Letters Patent is:—

1. In an internal combustion motor, the combination, with a fuel pump having a main plunger, and means for operating the said main plunger, of an auxiliary plunger for said pump, means for moving said aux-

iliary plunger in synchronism with the main plunger, and means controlled by the speed of the engine for varying the amount of such synchronous movement of the auxiliary plunger. 45

2. In a fuel pump for internal combustion engines, a pump chamber, a main plunger working therein, an auxiliary plunger, means for yieldingly withdrawing the auxiliary plunger from the pump chamber, in combination with a stop on said auxiliary plunger for limiting the downward movement thereof, a stroke regulator member acting against a shoulder on said auxiliary plunger adapted to raise said plunger, means controlled by the speed of said engine for changing the position of said stroke regulating member thereby regulating the stroke of said auxiliary plunger. 50 60

3. In a fuel pump for internal combustion engines, a pump chamber, a main plunger working therein, means for operating said main plunger, an auxiliary plunger, means for yieldingly withdrawing said auxiliary plunger from the pump chamber, said auxiliary plunger provided with a shoulder, in combination with a lever connected with and operated from the engine shaft and arranged to strike the shoulder during a portion of its movement to thereby lift the same, means controlled by the speed of the engine to regulate the stroke of said auxiliary plunger, a stop for limiting the downward movement of said auxiliary plunger. 70 75

In testimony whereof I hereunto affix my signature in the presence of two witnesses.

OTTO LIETZENMAYER.
